(57) **CLAIM**

The ornamental design for a bristled portion of a brush, as shown and described.

DESCRIPTION

This application claims priority from U.S. patent application Ser. No. 10/601,708, filed June 23, 2003, which is incorporated herein by reference in its entirety.

FIG. 1 is a top plan view of a bristled portion of a brush showing our new design.

FIG. 2 is a bottom plan view thereof.

FIG. 3 is a right side view thereof, the left side view being a mirror image.

FIG. 4 is front end view thereof; and,

FIG. 5 is a rear end view thereof.

The portions of the drawings appearing in broken line are for environment only and do not form a part of the design.

1 Claim, 4 Drawing Sheets
